CLAIM

The ornamental design for a flashlight with display, as shown and described.

DESCRIPTION

FIG. 1 is a perspective view of a flashlight with display showing my new design;

FIG. 2 is a front elevational view thereof;

FIG. 3 is a back elevational view thereof;

FIG. 4 is a right side elevational view thereof;

FIG. 5 is a left side elevational view thereof;

FIG. 6 is a bottom plan view thereof; and,

FIG. 7 is a top plan view thereof.

The broken lines shown in the figure drawings illustrate structure and form no part of the claimed design.
